US0D1034909S

(12) **United States Design Patent** (10) **Patent No.:** **US D1,034,909 S**
(45) **Date of Patent:** **** Jul. 9, 2024**

(54) **CROSSHEAD FRAME**

(71) Applicant: **Kerr Machine Co.**, Sulphur, OK (US)

(72) Inventors: **Kelcy Jake Foster**, Ardmore, OK (US); **Micheal Cole Thomas**, Ardmore, OK (US); **Christopher Todd Barnett**, Stratford, OK (US); **Nicholas Son**, Davis, OK (US); **John Keith**, Ardmore, OK (US); **Mark S. Nowell**, Ardmore, OK (US); **Guy J. Lapointe**, Sulphur, OK (US); **Michael Eugene May**, Ardmore, OK (US)

(73) Assignee: **Kerr Machine Co.**, Sulphur, OK (US)

(**) Term: **15 Years**

(21) Appl. No.: **29/784,347**

(22) Filed: **May 19, 2021**

(57) **CLAIM**

The ornamental design for a crosshead frame, as shown and described.

DESCRIPTION

FIG. 1 is a front, right side perspective view of a crosshead frame of our new design;

FIG. 2 is a rear, right side perspective view thereof;

FIG. 3 is a front, left side perspective view thereof;

FIG. 4 is a rear, left side perspective view thereof;

FIG. 5 is top plan view thereof;

FIG. 6 is a bottom plan view thereof;

FIG. 7 is a front elevational view thereof;

FIG. 8 is a rear elevational view thereof;

FIG. 9 is a right side elevational view thereof; and,

FIG. 10 is a left side elevational view thereof.

The broken lines shown in the figures are for the purpose of illustrating portions of the crosshead frame and form no part of the claimed design.

1 Claim, 10 Drawing Sheets
